(57) **CLAIM**

The ornamental design for a cosmetic dispenser, as shown and described.

DESCRIPTION

FIG. 1 is a perspective view of a cosmetic dispenser; FIG. 2 is a front elevation view of the cosmetic dispenser of FIG. 1;

FIG. 3 is a back elevation view of the cosmetic dispenser of FIG. 1;

FIG. 4 is a left side elevation view of the cosmetic dispenser of FIG. 1;

FIG. 5 is a right side elevation view of the cosmetic dispenser of FIG. 1;

FIG. 6 is a top plan view of the cosmetic dispenser of FIG. 1; and,

FIG. 7 is a bottom plan view of the cosmetic dispenser of FIG. 1.

The broken lines form no part of the claimed design. The claimed design extends to the broken line boundary but does not include the boundary.

1 Claim, 4 Drawing Sheets
